UNITED STATES PATENT OFFICE.

EDWARD PARTINGTON, OF GLOSSOP, ENGLAND.

APPARATUS FOR RECLAIMING PAPER PULP AND THE LIKE FROM THE WASTE WATERS IN PAPER-MAKING MACHINES.

1,409,885.

Specification of Letters Patent. Patented Mar. 14, 1922.

Application filed November 30, 1921. Serial No. 518,805.

To all whom it may concern:

Be it known that I, EDWARD PARTINGTON, a subject of the King of Great Britain and Ireland, and a resident of Glossop, in the 5 county of Derby, England, have invented a certain new and useful Apparatus for Reclaiming Paper Pulp and the like from the Waste Waters in Paper-Making Machines, (for which I have filed an application in 10 Great Britain, No. 14030, filed May 21, 1920,) of which the following is a specification.

This invention relates to the reclaiming of paper pulp and the like from the "save-all" or "back" water in paper-making ma- 15 chines.

In paper-making machines, the water which passes through the "wire" and collects in the "save-all" troughs therebelow flows to a tank or receptacle whence it is 20 pumped to a chest or the like alongside the top stock chest or chests. From the chest or the like, which is provided with rotary paddles, similar to those of the stock chest or chests, to keep the pulp or fibres etc. in 25 the water in a state of suspension, part of the water is drawn off for mixing with pulp which flows from the stock chests to the sand boxes, while the excess passes off through an overflow for treatment for the recovery of 30 the fibres, pulp, etc.

The object of this invention is to provide an improved apparatus for reclaiming from the "save-all" or "back water," the fibres or pulp suspended therein, whereby the excess 35 water which overflows from the chest or the like aforesaid shall be clear and free from fibres or pulp, and water containing any desired quantity of fibres or pulp may be drawn off from the chest or the like for mix- 40 ing with the pulp from the stock chest or chests.

According to the invention, the "save-all" or "back" water containing pulp or fibres in suspension is introduced gently into a chest 45 or other receptacle at or near the bottom thereof and the mixture in the lower part of the chest or receptacle is kept in constant gentle movement so that while the suspended pulp or fibres is or are allowed to 50 settle or gravitate towards the bottom of the chest or receptacle, leaving the liquid in the upper part thereof clear, it is or they are prevented from depositing on the bottom of the chest or receptacle and are maintained 55 in suspension in the lower part of the chest

or receptacle, which latter is provided with draw-off outlets arranged at different levels.

In the accompanying drawing, Fig. 1 is a vertical section and Fig. 2 a plan of one arrangement of apparatus applicable for 60 carrying the invention into effect.

Referring to the drawing, 2 is a chest within and close to the concaved bottom of which is or are arranged one or more rotary paddles 3 conveniently carried by a central 65 vertical shaft 4, supported from above in a bearing 5, carried by cross-members 6, and adapted to be slowly rotated by bevel gear- 70 ing 7, a shaft 8 also mounted in bearings carried by the cross-members, and fast and loose pulleys 9.

The chest is provided at the bottom with an inlet 10 and at the top with an overflow outlet 11. Between the inlet 10 and overflow 75 11, one or more valve-controlled draw-off outlets 12 is or are arranged at an appropriate level or levels, and a valve controlled outlet 13 is arranged in the centre of the bottom of the chest.

In operation, the "save-all" or "back" 80 water may be pumped into a box or trough arranged above the chest 2, and may gravitate through a valve-controlled pipe from the box or trough to the inlet 10 so as to enter the chest 2 gently. The water entering 85 the chest 2 by the inlet 10 is spread or distributed across the area of the chest by the slowly rotating paddle or paddles 3 which keep the water in the lower part of the chest in constant gentle movement. The paddle 90 or paddles 3 is or are so rotated that the constant gentle movement imparted by it or them to the water in the lower part of the chest is not sufficient to so disturb the water in the upper part of the chest as to 95 prevent the fibres, etc., therein from settling towards the bottom of the chest, but is sufficient to prevent the fibres, etc., in the water in the lower part of the chest from depositing on the bottom of the latter, and to maintain the fibres, etc., in suspension in the lower part of the chest, by which means the suspended fibres, etc., act to some extent as a filtering medium for the fibres, etc., in the incoming water.

Water containing fibres, etc., in suspension can be drawn off by the outlet 12 for mixing with the pulp, and where a plurality of outlets are provided at different levels water containing varying amounts of fibres, etc., 110

in suspension can be drawn off. Any excess of water passes away by the overflow 11 at the top as clear water. When the fibres, etc., in suspension in the lower part of the chest 5 become too dense, the water or a portion of the water in the lower part of the chest may be run off through the outlet 13 for further treatment for the separation and recovery of the fibres, etc., or to the beating engines or 10 as required.

What I claim as my invention and desire to secure by Letters Patent is:—

An apparatus for reclaiming paper pulp and the like from the waste waters of paper 15 making machines comprising a cylindrical tank having an open top and having a bottom dished downwardly at the center and provided at the central lowest point with a draw off opening for the removal of deposited material, a valve controlling said 20 opening, a supply pipe for the introduction of the waste water and opening laterally into the tank immediately above the bottom,

a valve for regulating the flow of waste water through said supply pipe whereby to 25 insure a slow entry of the waste water into the tank, a plurality of draw off openings diametrically opposite the supply pipe and positioned at different levels above the bottom, valves controlling said draw off openings, an overflow opening directly above the draw off openings and adjacent the top of the tank, a shaft extending axially from the top of the tank downward and terminating near the bottom, an arm extending 30 from said shaft and having a curvature corresponding to the curvature of said bottom, said arm being positioned slightly above and free from the bottom throughout whereby to avoid scraping action on said bottom, 35 said arm being also of slight thickness vertically to avoid undue agitation of the tank contents, and means to rotate said shaft.

In witness whereof I have hereunto set my hand.

EDWARD PARTINGTON.
